(57) **CLAIM**

The ornamental design for an image forming apparatus with toner cartridge, as shown.

DESCRIPTION

FIG. 1 is a front view of an image forming apparatus with toner cartridge showing our new design;

FIG. 2 is a rear view thereof;

FIG. 3 is a top plan view thereof;

FIG. 4 is a bottom plan view thereof;

FIG. 5 is a right side view thereof;

FIG. 6 is a left side view thereof;

FIG. 7 is a front, top, left side perspective view thereof;

FIG. 8 is a rear, top, right side perspective view thereof;

FIG. 9 is a front, bottom, right side perspective view thereof;

and,

FIG. 10 is a rear, bottom, left side perspective view thereof.

1 Claim, 6 Drawing Sheets
